(57) **CLAIM**

I claim the ornamental design for an external nasal dilator, as shown and described.

DESCRIPTION

FIG. 1 is a top plan view of a first embodiment of a nasal dilator showing my new design;

FIG. 2 is a perspective view thereof, shown in a state of use; FIG. 3 is a three-quarter perspective view thereof; FIG. 4 is a top plan view of a second embodiment of a nasal dilator showing my new design; FIG. 5 is a perspective view thereof, shown in a state of use; FIG. 6 is a three-quarter perspective view thereof; FIG. 7 is a top plan view of a third embodiment of a nasal dilator showing my new design; FIG. 8 is a perspective view thereof, shown in a state of use; FIG. 9 is a three-quarter perspective view thereof; FIG. 10 is a top plan view of a fourth embodiment of a nasal dilator showing my new design; FIG. 11 is a perspective view thereof, shown in a state of use; FIG. 12 is a three-quarter perspective view thereof; FIG. 13 is a top plan view of a fifth embodiment of a nasal dilator showing my new design; FIG. 14 is a perspective view thereof, shown in a state of use; FIG. 15 is a three-quarter perspective view thereof; FIG. 16 is a top plan view of a sixth embodiment of a nasal dilator showing my new design; FIG. 17 is a perspective view thereof, shown in a state of use; FIG. 18 is a three-quarter perspective view thereof; FIG. 19 is a top plan view of a seventh embodiment of a nasal dilator showing my new design; FIG. 20 is a perspective view thereof, shown in a state of use; FIG. 21 is a three-quarter perspective view thereof; FIG. 22 is a top plan view of an eighth embodiment of a nasal dilator showing my new design; FIG. 23 is a perspective view thereof, shown in a state of use; and, FIG. 24 is a three-quarter perspective view thereof. The broken line showing of human facial features is directed to environment and is for illustrative purposes only; the broken lines form no part of the claimed design.
